(57) CLAIM

The ornamental design for a gun rack set, as shown and described.

DESCRIPTION

FIG. 1 is a first perspective view of a first element of a gun rack set showing our new design;

FIG. 2 is a second perspective view of the first element thereof;

FIG. 3 is a front view of the first element thereof;

FIG. 4 is a back view of the first element thereof;

FIG. 5 is a left side view of the first element thereof;

FIG. 6 is a right side view of the first element thereof;

FIG. 7 is a top view of the first element thereof;

FIG. 8 is a bottom view of the first element thereof;

FIG. 9 is a first perspective view of a second element of a gun rack set showing our new design;

FIG. 10 is a second perspective view of the second element thereof;

FIG. 11 is a front view of the second element thereof;

FIG. 12 is a back view of the second element thereof;

FIG. 13 is a left side view of the second element thereof;

FIG. 14 is a right side view of the second element thereof;

FIG. 15 is a top view of the second element thereof;

FIG. 16 is a bottom view of the second element thereof;

FIG. 17 is a front perspective view of a gun rack set shown assembled in a first configuration;

FIG. 18 is a back perspective view thereof;

FIG. 19 is a front perspective view of the gun rack set shown assembled in a second configuration;

FIG. 20 is a back perspective view thereof;

FIG. 21 is a front perspective view of the gun rack set shown assembled in a third configuration;

FIG. 22 is a back perspective view thereof;

FIG. 23 is an enlarged view of the selected portion 23 in FIG. 1;

FIG. 24 is an enlarged view of the selected portion 24 in FIG. 2;

FIG. 25 is an enlarged view of the selected portion 25 in FIG. 9; and,

FIG. 26 is an enlarged view of the selected portion 26 in FIG. 17.

The broken lines shown in the drawings depict portions of the gun rack set that form no part of the claimed design. The dot dash broken lines in the drawings depict reference to the enlargements and form no part of the claimed design claim.

1 Claim, 26 Drawing Sheets
